CLAIM

The ornamental design for a handle for pipe coupling and decoupling tool, as shown and described.

DESCRIPTION

FIG. 1 is a right front perspective view of a handle for pipe coupling and decoupling tool showing my new design;

FIG. 2 is a rear elevational view thereof;

FIG. 3 is a left side elevational view thereof;

FIG. 4 is a top plan view thereof;

FIG. 5 is a bottom plan view thereof;

FIG. 6 is a perspective view thereof, shown in a reduced scale;

FIG. 7 is a perspective view of a second modified embodiment thereof;

FIG. 8 is a front elevational view of FIG. 7, shown separately for clarity of illustration; and,

FIG. 9 is a rear perspective view of FIG. 7, shown in a reduced scale.

The broken line portion of FIGS. 6 and 9 are for illustrative purposes only and form no part of the claimed design.
